DESIGN FOR A CALENDAR OR SIMILAR ARTICLE

Arthur M. Gordon and Alred L. Gordon,
Cleveland, Ohio

Application January 23, 1934, Serial No. 50,490

Term of patent 14 years

To whom it may concern:

Be it known that we, ARTHUR M. GORDON and ALRED L. GORDON, citizens of the United States, residing at Cleveland, in the county of Cuyahoga and State of Ohio, have invented a new, original, and ornamental Design for a Calendar or Similar Article, of which the following is a specification, reference being made to the accompanying drawing, forming a part thereof.

The figure in the drawing is a plan view of a

calendar showing our design, the same having no substantial thickness.

The characteristic or outstanding feature of the design resides in the bird element which is made of feathers.

We claim:

The ornamental design for a calendar or similar article, as shown and described.

ARTHUR M. GORDON.
